WELDLESS ELEVATOR LINK

Filed Sept. 23, 1929

INVENTOR.
GEORGE W. MOORE.
BY.

H. D. Duckman

ATTORNEY.

UNITED STATES PATENT OFFICE

GEORGE W. MOORE, OF LONG BEACH, CALIFORNIA

WELDLESS ELEVATOR LINK

Original application filed November 18, 1927, Serial No. 234,228. Divided and this application filed September 23, 1929. Serial No. 394,671.

An object of my invention is to provide a link for tubing or casing elevators which is simple to manufacture, and one which will not readily break under severe strain. Heretofore elevator links have been formed by bending a rod at its center, the free ends then being brought together and welded, the joint thus occurring at the point where the hook engaged the link, and under severe strain this weld would frequently break. The breaking of the link is extremely dangerous to the workmen, and also may severely damage the well, by reason of the fact that the tubing or casing drops down into the hole.

Another object of my invention is to provide a weldless link which is formed with a very few operations, such operations being simple and quickly performed.

23 A further object of invention is to provide a weldless link with a hand grip thereon so that the operator can more readily grasp and manipulate the link.

Other objects, advantages and features of 25 invention may appear from the accompanying drawings, the subjoined detailed description and the appended claims.

This application is a division of my co-pending application on Weldless elevator 30 link, Serial Number 234,228, filed November 18, 1927.

In the drawings:

Figure 1 is a side elevation of the rod from which the link is made.

25 Figure 2 is a side elevation of the rod in the next stage of manufacture.

Figure 3 is a side elevation of the rod in the third step of completion.

40 Figure 4 is a plan view of the completed rod.

Figure 5 is a side elevation of the same.

Figure 6 is a side elevation of my links in position on an elevator.

45 Referring more particularly to the drawings, my weldless rod is formed in a series of steps starting with a rod 1, of substantially uniform diameter through its length. This rod being then moved through the rollers forming the structure as shown in Figure 2, 50 consists of a central circular cross section 2,

the ends 3, 4, being of substantially the same diameter as the rod 1, with which I start. During this rolling operation, the rod is elongated to the required length, which length varies from 6 feet to 8 feet, more or less. The rolling operation is so controlled that each rod is made exactly the same length; this insures a uniform strain on the two links which support the elevator.

The next step consists in flattening the 60 ends 3, 4, as shown at 5, 6. The central section 2 remains undisturbed. The next operation consists in cutting the openings 7, 8 to form the eyes 9, 10. The opening 7, which extends over the elevator lugs is 65 smaller in size than the opening 8, which is engaged by the block hook. That is the opening 7, is smaller in dimension along the longitudinal axis of the link than the opening 8.

The upper end of the eye 10 is flattened as at 11, and is bent upwardly at an angle. The purpose of the flattening is to provide 70 more metal along the line of greatest strain, and the bending is to enable the two links to fit more closely together when in use on an elevator as shown in Figure 6.

The central section 2 tapers gradually 75 outwardly into the eyes 9, 10, so that no abrupt angles are formed across which a 80 break can occur. The gradual tapering distributes the strain more equally and there is less likelihood of a fracture occurring at the point where the eyes and the central section come together.

85 It is obvious that the above described method can be accomplished by forging the rod into shape as well as by rolling the same, and also it may be desirable to make the end 3 slightly smaller in diameter than the end 4, by reason of the fact that the eye 9 is smaller than the eye 10.

When the links are in actual use, one of the operators stands a considerable distance 90 above the floor of the derrick on a specially provided platform, and as the elevator passes him, he reaches out and grasps the links to pull the pipe over into the rack. To provide a convenient hand grasp, a pair of loops 12-12 are formed one on either end 95 100

of the link, and these loops may be either welded to the link or may be integrally formed thereon during the manufacturing process. A cable or rod 13, or any other rigid or flexible member, is secured to both of the loops and extends between them, thus forming a hand grasp for the operator so that the links may be more readily manipulated.

10 In the rolling operation, and in the cutting of the eyes 9—10, it is desirable that the cross sectional area of the central section 2 be about the same as the sum of the cross sectional area of both sides of the loop, thus making all parts of the link substantially the same in tensile strain.

Having described my invention, I claim:

1. A weldless elevator link for oil well elevators formed of a single piece of metal, said link comprising a straight central section, enlarged ends on said piece, eyes cut in said enlarged ends, a loop on said link on both ends thereof and a hand grasp secured to said loops.

2. A weldless elevator link for oil well elevators formed of a single piece of metal, said link comprising a straight central section, enlarged ends on said piece, eyes cut in said enlarged ends and hand grasp means extending substantially the length of said link, and means securing said hand grasp means to the link.

3. A weldless elevator link for oil well elevators formed of a single piece of metal, said link comprising a straight central section, enlarged ends on said piece, eyes cut in said enlarged ends, a loop on said link on both ends thereof and a cable secured to said loops whereby a hand grasp is provided.

4. A weldless elevator link for oil well elevators formed of a single piece of metal, said link comprising a straight central section, enlarged ends on said piece, eyes cut in said enlarged ends, one of said enlarged ends being flattened and bent at an angle with the central section thereof, hand grasp means extending substantially the length of said link, and means securing said link and the hand grasp means.

50 In testimony whereof, I affix my signature.
GEORGE W. MOORE.
